Attorneys.

Patented Oct. 2, 1923.

UNITED STATES PATENT OFFICE.

MILLARD F. PIERCY, OF BALTIMORE, MARYLAND.

TOY.

Application filed October 20, 1922. Serial No. 595,709.

To all whom it may concern:

Be it known that MILLARD F. PIERCY, a citizen of the United States, residing at Baltimore, in the State of Maryland, has invented certain new and useful Improvements in Toys, of which the following is a specification.

This invention relates to an improvement in toys and has particular reference to an exceedingly simple and cheap toy which will afford amusement for children.

The invention is illustrated in the accompanying drawing, wherein,—

Fig. 1. shows the same in side elevation.

Fig. 2. illustrates the same in front elevation, and

Fig. 3. shows portions of the toy in top or plan view, and in broken lines indicates the positions of the parts when set for operation, as the same would appear if viewed on the line 3—3 of Fig. 1.

Referring to the drawing the numeral 4 designates a base-bar which carries a post or stem 5 that extends vertically therefrom at a point intermediate the ends of the said bar. This post is short and rigid with respect to the bar and serves as a pivot bearing as will presently be more fully explained.

The base also carries a wire frame comprising a vertical portion 6 which extends upwardly from a point in front of the post 5, and has a horizontal stretch 7 which extends rearwardly from the portion 6 but in an elevated position above or with respect to the base. This horizontal stretch of the frame carries a depending prong 8 which extends or points downwardly in a vertical plane or alinement with the upwardly-extending post or stem 5 but is spaced above the latter.

In the present instance the wire frame is attached to the base by forming a lateral prong 9 on the lower end of the vertical portion 6 and driving this prong into the front end of the base.

In carrying out my invention I make use of a captive ball and a device for striking the same and to increase the interest of a child in playing with the toy, I impart to the striking device a form imitative of a base-ball batter. This striking device therefore consists of a block 10, cut roughly to imitate the form of a batter with outstretched arms 11 from which a bat 12 extends.

This block 10, has an upper recess 13 and a lower recess 14,—the lower recess seating on the upper end of the post or stem 5 and the upper recess receiving the lower end of the depending prong 8. Thus it will be understood that the block 10 is pivotally sustained between the post 5 and the prong 8, so it may be oscillated between said two pivots.

It will be noted that the block is so mounted between the post and prong that the bat 12 will extend laterally toward the vertical portion 6 of the wire frame but will clear or pass said portion 6 as the block is turned or oscillated between its pivots.

In further carrying out my invention I provide means for yieldingly swinging the block in one direction which in the form illustrated consists of a coiled spring 15 which is wound about the post or stem 5 with one end 16 held in the base and the other end 17 held to the block, as shown in Fig. 1.

From the base there projects an arm 18 which has an upturned end which lies in the path of a portion of the block and forms a stop to limit the swinging movement of the block.

The coiled spring 15 is under sufficient tension to normally keep the block against the stop-arm 18, as clearly shown in Fig. 3 of the drawing.

For convenience in operation, I preferably provide a pin 19 which is attached to and projects laterally from the block 10 whereby the same may be engaged by the finger 20 of the operator, as indicated by broken lines in Fig. 3 whereby to swing the block to the dotted-line position shown in said Fig. 3, against the tension of the spring 15, in which position it is in readiness for operation.

To complete the toy, I provide a ball 21 which is attached to a cord 22, preferably of elastic, which cord is fastened to the horizontal stretch 7 of the wire frame so that the ball may be suspended in a horizontal plane in alinement with the path through which the bat 12 will swing.

The operation is simple and as follows:

The operator will engage the pin 19 with the finger and swing the block 10 around to the dotted-line position shown in Fig. 3, which operation will wind the spring 15. The finger 20, is then removed and the block will immediately swing forward toward the

stop 18 and carry the bat 12 through a path which will cause it to strike the ball. When the ball is struck, it will be projected, and being held by the cord 22, will be thrown through a circular or a spiral path which will cause the cord to be wound on the horizontal stretch 7 of the wire frame with some force, and frequently with sufficient force to cause it to unwind.

10 No particular rules are required inasmuch as the toy is merely designed for the amusement of a child.

Having described my invention, I claim,—
A toy comprising a base, a wire frame ex-

tending upwardly from the base and projecting rearwardly and terminating in a downturned prong, a stem projecting upwardly from the base, a block pivotally engaged at its upper end by the prong and pivotally engaged by the stem, a spring coiled about the stem and engaging the block to swing the latter in one direction, a stop to limit the swinging movement of the block, and a ball suspended in the path of the block to be struck by the latter during its swinging movement.

15 In testimony whereof I affix my signature.
MILLARD F. PIERCY.
